UNITED STATES PATENT OFFICE.

GUNARD G. FRIEBERG, OF FREDERIC, WISCONSIN.

STANCHION.

1,080,755.

Specification of Letters Patent.

Patented Dec. 9, 1913.

Application filed April 10, 1913. Serial No. 760,345.

To all whom it may concern:

Be it known that I, GUNARD G. FRIEBERG, a citizen of the United States, residing at Frederic, town of Daniels, in the county of Burnett and State of Wisconsin, have invented a new and useful Stanchion; and I do hereby declare the following to be a full, clear, and exact description of the invention, such as will enable others skilled in the art 10 to which it appertains to make and use the same.

This invention relates to a new and useful stanchion for cattle stalls.

As an object of the invention it is the 15 aim to provide means for opening or closing a plurality of stanchions simultaneously.

In practical fields the details of construction may necessitate alterations, to which the patentee is entitled, provided the alterations fall within the scope of what is 20 claimed:

The invention comprises further features and combination of parts, as hereinafter set forth, shown in the drawings and claimed.

25 In the drawings:—Figure 1 is a view in elevation of one or more stanchions, showing the same closed. Fig. 2 is a similar view, showing the stanchions opened. Fig. 3 is an enlarged detail view of the upper portion of the stanchions. Fig. 4 is an enlarged detail view of the lock.

Referring more especially to the drawings, 1 designates the base of the stall, rising from which are a series of posts or standards 3, there being two to each stanchion. These standards or posts connect in any suitable manner at 4 to the upper bars 5, to which are secured by means of bolts or other fastenings 6, brackets 7, which form 30 bearings for the reciprocating rod 8. Mounted upon the rod are sleeves 9, between the ends of each of which upon the bolts 10, a cable or chain 11 is secured, the purpose of which will presently appear. Pivoted upon a pin 12 secured in the base of 45 each stall is a frame 13, comprising a vertical rod 14 having at its ends transverse rods or tubes 15 and 16. Pivoted to the lower rods or tubes 16 are the oscillating 50 stanchion bars 17, the upper ends of which terminate in beveled portions 18, which are designed to engage the notches 19 of the pivoted latch members 20, which are pivoted to the rods or tubes 15. Also pivoted upon 55 the same pivot as the latch members are the U-shaped stanchion holders 21, in which the

stanchion bars are movable, that is, when the holders are thrown upwardly and outwardly. The holders 21 are provided with anti-frictional rollers 22 to engage the stanchion bars, when allowing the holders to fall in place as shown in Fig. 1 by gravitation, thereby closing the stanchion bars, so that the upper beveled end of the stanchion bars will engage the notches of the latch members 19. The upper bars or tube 15 have a chain connection 23 with the bars 5, on which the pulleys 24 are mounted. The chains or cables 11 pass over the pulleys 24 and are connected to the latches 19, which latches, when raised, by reciprocating the rod 9, engage under the extensions 25 of the stanchion holders 21. The latch members 19 are first operated sufficiently to allow the beveled ends of the stanchion bars 17 to be free of the notches of the latch members, then the latch members engage under the extensions 25, so that the holders 21 will be oscillated on their pivots, thereby allowing the stanchion bars 17 to fall open 80 outwardly and partly downwardly, by gravitation, until limited by the anti-frictional rollers 22. Coil springs 27 connect the bars or rods 16 to the base of the stalls, in order to hold the frames 13 yieldably in 85 position.

The spring 28 connects between the rod 9 and the bar 5. Mounted in a bracket 29 of one of the standards 3 is a pulley 30, over which a cable or chain 31 passes, one end of 90 which is connected to a sleeve 32 on the rod 9, while the other end is connected to an eye 33 of one of the sections 34 of the lever 35. The lever 35, or rather the section 34 thereof, is pivoted at 36 to the standard or post 3, 95 there being a dog 37 to engage any one of the two teeth of the segment 38 to hold the lever down or up. This dog 37 may be disengaged from the notches or teeth of the segment 38, by pulling upon the flexible rod 100 39. By throwing the lever 35 downwardly on its pivot 36 the rod 8 may be reciprocated to operate the stanchion bars. It will be seen that the lever 35 comprises the two sections 34 and 40 pivoted together at 41. 105 When operating the lever, the extension 42 of the section 40 engages the section 34, as will be understood, in order that the lever may act as a rigid rod when being moved downwardly. After the lever 35 is swung or 110 oscillated downwardly on its pivot 36, and held in such position by the dog 37 engag-

ing a notch of the segment 38 as shown in Fig. 2, the section 40 of said lever 35 may be thrown upwardly on its pivot 41, as shown in Fig. 2.

5 The invention having been set forth, what is claimed as new and useful is:—

1. In an apparatus as set forth, a pivoted stanchion frame having a pivoted stanchion bar, a U-shaped stanchion holding member

10 pivoted to the upper portion of said frame, a latch member to be engaged by said stanchion bar, said holding member having an extension to be engaged by the latch member subsequently to releasing the stanchion bar

15 for operating the holding member upon further movement of the latch member to allow the stanchion bar to open automatically by gravitation, and means for actuating the latch member.

20 2. In an apparatus as set forth, a pivoted automatically gravity opening stanchion bar, a latch member therefor, and a U-shaped holding member actuated by the latch member to allow the stanchion bar to automatically open, and means for actuating the latch member.

25 3. In an apparatus as set forth, a pivoted automatically gravity opening stanchion bar, a latch member therefor, and a U-shaped holding member actuated by the latch mem-

ber to allow the stanchion bar to automatically open, and means for actuating the latch member, said latch member when released by said means restoring the holding member to its normal position by gravitation, and the 35 weight of said holding member closing the stanchion bar.

4. In an apparatus as set forth, a pivoted stanchion frame having a pivoted stanchion bar, a U-shaped stanchion holding member 40 pivoted to the upper portion of said frame, a latch member to be engaged by said stanchion bar, said holding member having an extension to be engaged by the latch member subsequently to releasing the stanchion bar 45 for operating the holding member upon further movement of the latch member to allow the stanchion bar to open automatically by gravitation, a reciprocating rod, a lever mechanism having connections with said rod 50 to operate the same, and connections between the rod and the latch member.

In testimony whereof I have signed my name to this specification in the presence of two subscribing witnesses.

GUNARD G. FRIBERG.
